(57) **CLAIM**

We claim the ornamental design for a transitional image for a mobile phone, as shown and described.

DESCRIPTION

FIG. 1 is a front perspective view of a transitional image for a mobile phone;

FIG. 2 is a front view of the image for mobile phone of FIG. 1;

FIG. 3 is another front view of the image for mobile phone of FIG. 1;

FIG. 4 is another front view of the image for mobile phone of FIG. 1;

FIG. 5 is another front view of the image for mobile phone of FIG. 1; and,

FIG. 6 is another front view of the image for mobile phone of FIG. 1.

The broken line showing of a mobile phone is not claimed.

The appearance of the transitional image sequentially transitions between the images shown in FIGS. 1-6. The process or period in which one image transitions to another image forms no part of the claimed design.
